(57) **CLAIM**

The ornamental design for a display screen with animated graphical user interface, as shown and described.

DESCRIPTION

FIG. 1 is the first image in a sequence for a display screen with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the first image in a sequence for a display screen with animated graphical user interface showing an alternative embodiment of our new design;

FIG. 10 is the second image thereof;

FIG. 11 is the third image thereof;

FIG. 12 is the fourth image thereof;

FIG. 13 is the fifth image thereof;

FIG. 14 is the sixth image thereof;

FIG. 15 is the seventh image thereof; and,

FIG. 16 is the eighth image thereof.

The appearance of the animated graphical user interface sequentially transitions between the images shown in FIGS. 1-8 and FIGS. 9-16. The process or period in which one image transitions to another forms no part of the claimed design.

The outermost broken-line perimeter illustrates a display screen and forms no part of the claimed design. The remaining broken lines illustrate portions of a graphical user interface and form no part of the claimed design.
